MECHANISMS FOR THE CALCULATION OF FUNCTIONS WITH SEVERAL VARIABLES

Jiří Harlas, Prague, Czechoslovakia

Application April 11, 1936, Serial No. 73,980
In Czechoslovakia September 1, 1932

3 Claims. (Cl. 235—61)

My invention relates to improvements in mechanisms for the calculation of functions with several variables, more particularly for military purposes, for instance, for anti-aircraft service, 5 being a continuation in part of the applications filed May 3, 1933 under Serial Number 669,087 and December 4, 1934 under Serial Number 755,997, Mechanisms for the calculation of functions with several variables.

10 The object of my invention is to replace a system of curves hitherto used together with three variables, by a single moving curve applied mechanically and shifted by a combined movement as a function of one of the given variables.

15 Another object is to provide such a device which is simple and easily handled and used.

A further object is to have a device of this character wherein the operation is fundamentally based upon the movements and positions of a 20 swingably mounted curvilinear member.

Other objects and advantages will appear more fully hereinafter as the specification proceeds.

The nature of the invention is graphically explained with reference to the drawings, in which 25 Figure 1 shows diagrammatically the problems arising when it is attempted to train a gun at, or to locate a movable target such as an airplane.

Figure 2 shows one of the mechanisms hitherto used for this purpose, now serving as a basic from 30 which to figure herein.

Figures 3, 4 and 5 show diagrammatically the method of calculation used according to my invention.

Figure 6 shows a plan elevation, Figure 7 a cross-section and Figure 8 a perspective view of a device made according to the invention.

The device as illustrated serves for quick mechanical ascertaining of the so called reduced 40 distances ρ , necessary in commanding anti-aircraft search lights, i. e. the actual distance of the airplane under observation having regard to the necessary correction of the acoustic aberration (parallax). This reduced distance is a component for further calculations which however 45 do not come into consideration in this connection.

The device will first be explained theoretically in its application for ascertaining the so called 50 reduced distance necessary for directing or aim-

ing anti-aircraft guns and search lights. The value of ρ is given by the equation

$$I \quad \rho = \frac{c \cdot k}{1 + Z \cdot \sin \epsilon a} \quad 5$$

wherein

c is the speed of sound (333 metres per second),

k is reduction constant, selected for the device,

ϵa is the acoustic site or angle, and

Z is a variable given by the equation

$$II \quad Z = \frac{\theta c}{y} \quad 10$$

wherein

θ is dead time of operation, ascertained by actual test, and

y is the altitude in metres of the airplane under observation.

We convert this function into the form of a polar diagram as shown in Figure 3 of the drawings where the curves represent the different 20 values of Z .

The value Z although theoretically a variable, is however in practice a constant. For a certain trained team of soldiers and for a certain given mechanism the dead time of operation can be assumed as a constant, and an airplane, intent on bombing or photographing, flies as a rule in an altitude which does not vary perceptibly or suddenly, so that y is also a constant.

One finds from a study of this system of curves that the different curves can be replaced by a single curve—which may be called moving curve—which passes constantly through the point a and which makes the two movements:

1. Rotation about the point a ,

2. Translation through the point a so that its path coincides with the path of the different curves Z of the diagram.

The two movements of the moving curve are merely the functions of Z .

Consequently it is unnecessary to trace the Z system of curves. It suffices to have the moving curve passing through the point a and to move it as a function of Z to the necessary positions.

When utilizing this moving curve there is no necessity for interpolation; it is sufficient to follow up the moving curve by an index to obtain the value of ρ in the form of a translation with reference to the starting point 0 .

The device embodying my invention comprises

a curvilinear member 1 of metal or the like, having a slot which represents the moving curve. Member 1 is guided by means of a pulley 2 which is journaled by means of member 46 on the frame 5 47 so that it can both oscillate round said pulley and slide upon said slot, and is hinged at b by means of a pin 4 to a lever 5 which is journaled at m in bearings 6. Worm-wheel 15 is fixed to the other end of the lever 5 and meshes with a 10 worm 16 disposed on the spindle 17, the latter carrying a second worm 18 which meshes with a worm-wheel 7 connected with a disc 8 by means of spindle 9, journaled in bearings 24. Spindle 17 is provided with a hand-wheel 18 and is journaled in bearings 19 and 20. On the face of the 15 disc 8 are marked a group of curves I to VI, representing the different values of the dead time of operation from second to second. Adjacent to the face of the disc 8 are disposed two indicators 10 and 12 placed on a nut 21 adapted to be moved by means of a screw 22 which is provided with a knob 11 and journaled in bearings 23.

In the slot of the curvilinear member 1 a pulley 25 glides which is journaled on the member 26 which in turn is slidably guided in a guiding arm 14 rotatable about point 0.

The angle formed by the line Oa and the longitudinal axis (line Oc) of the guiding arm 14 correspond to the angle Ea, while the distance 30 Oc gives the value ρ which can be read on the scale provided on said arm in which case the mechanisms further referred to are superfluous.

According to the mode of execution illustrated and described however this value ρ is commuted 35 into a corresponding angle in order to be transferred to further mechanisms by means of the following auxiliary device which does not form an integral part of the invention but is described only in order to facilitate comprehension of the 40 operation of the device.

Arm 26 is provided with a toothed rack 27 which meshes with a pinion 28 connected by means of the spindle 29 with a bevel gear 30 and thereby with the shaft 31 of the planetary wheels 45 32 of a differential gear. Angle Ea is transmitted doubled from shaft 33 by toothed wheels 34 and 35 to one of the wheels 36 of the differential gear. Wheel 35 is connected with bevel wheel 37 which meshes with bevel wheel 38 of doubled radius; 50 bevel wheel 38 is turned therefore in angle of ϵ_a , and as it is connected by means of the hollow shaft 39 with the guiding arm 14, this angle ϵ_a is transferred to the latter. If the wheel 28 and the planetary wheels of the differential gear turn 55 through an angle of $\epsilon_a + \rho$ and the wheel 36 through an angle of $2\epsilon_a$, the wheel 40 and the shaft 41 will turn through an angle of ρ .

Shafts 29 and 39 are journaled in bearings 42, the differential gear in bearings 43 and 44, shaft 60 33 in bearings 45 and pulley 2 in bearings 46, all of which bearings are fastened to the frame 47.

In operation, indicator 12 is moved by means of knob 11 so that it is displaced on scale 18 in proportion to the value of the height y . Disc 8 is then turned by means of the hand-wheel 18 until the curve, for instance, I which corresponds to the given dead time of operation θ , intersects point 10. If shaft 33 is turned through angle Ea, shaft 41 is simultaneously turned through the 70 angle.

$$\rho = \frac{k.c}{1 + Z \sin \epsilon_a}$$

where

$$Z = \frac{\theta.c}{y}$$

Curves I to VI are plotted in the following manner:

Various values of Z correspond to various angles $\alpha, \beta, \gamma, \delta$ as indicated in Fig. 4. Value Z, however, depends on the value of θ and y , as indicated by 5 the equation

$$Z = \frac{\theta.c}{y}$$

Scale y is marked on the radius P on the disc 8, 10 as well as angles $2\alpha, 2\beta, 2\gamma$ and 2δ with regard to the same radius P. Curve I for the value $\theta=1$ is obtained by inserting the different values of y into the equation

$$Z = \frac{\theta.c}{y} \quad 15$$

Thus, for example, the intersection of curve I with line $Z=0.133$ has a distance from the center

$$y = \frac{1 \times 333}{0.1333} = 2500 \quad 20$$

with line $Z=0.333$ the distance

$$y = \frac{1 \times 333}{0.333} = 1000 \quad 25$$

In the same manner various points are obtained of curves II, III etc. for $\theta=2$ seconds, $\theta=3$ seconds etc.

The principal advantages of this device are as follows:

1. The variable result is obtained by means of a translation movement without interpolation.

2. The mechanism is simple and consequently accurate and practical.

The importance of the present invention increases in cases where it is necessary to obtain wholly by mechanical means ballistic or empirical functions of which the algebraic form is not precisely known.

What I claim is:

1. A device for calculating functions with several variables, comprising a curvilinear member having a slot, a pulley engaging in said slot, a link member hingedly connected to one end of said curvilinear member, a rotatable disc which carries on the face thereof a plurality of curves indicating different values of the dead time of operation from second to second, gearing operatively connecting said disc with said link member, a nut carrying two indicators and a scale indicating the height of the object to be followed, which scale is disposed adjacent to the face of said disc, a screw serving to move said nut along said scale, and an arm provided with a scale and swingable over said curvilinear member. 40 45 50 55

2. A device for calculating functions with several variables, comprising a curvilinear member having a slot, a pulley engaging in said slot, a link member hingedly connected to one end of said curvilinear member, a rotatable disc which carries on the face thereof a plurality of curves indicating different values of the dead time of operation from second to second, gearing operatively connecting said disc with said link member, a nut carrying two indicators and a scale indicating the height of the object to be followed, which scale is disposed adjacent to the face of said disc, a screw serving to move said nut along said scale, a swingable arm provided with a scale and consisting of two telescopic parts, and a pulley journaled on the outer part of said arm and engaging in the slot of said curvilinear member. 60 65 70 75

3. A device for calculating functions with several variables, comprising a curvilinear member having a slot, a pulley engaging in said slot, a 75

link member hingedly connected to one end of said curvilinear member, a rotatable disc which carries on the face thereof a plurality of curves indicating different values of the dead time of operation from second to second, gearing operatively connecting said disc with said link member, a nut carrying two indicators and a scale indicating the height of the object to be followed, which scale is disposed adjacent to the

face of said disc, a screw serving to move said nut along said scale, a swingable arm consisting of two telescoping parts, a pulley journaled on the outer part of said arm and engaging in the slot of said curvilinear member, and means for commuting the changing distance between the axis of rotation of said arm and the axis of said pulley into a corresponding angular value. 5

JIRI HARLAS.
